[57] CLAIM

The ornamental design for a tape cutter, as shown and described.

DESCRIPTION

FIG. 1 is a front elevational view of a tape cutter showing my new design;

FIG. 2 is a rear elevational view thereof;

FIG. 3 is a side elevational view thereof, the opposite side being a mirror image of that shown;

FIG. 4 is a top plan view thereof;

FIG. 5 is a bottom plan view thereof;

FIG. 6 is a front elevational view of an alternate embodiment thereof;

FIG. 7 is a rear elevational view of the embodiment of FIG. 6;

FIG. 8 is a side elevational view of the embodiment of FIG. 6, the opposite side being a mirror image of that shown;

FIG. 9 is a top plan view of the embodiment of FIG. 6;

FIG. 10 is a bottom plan view of the embodiment of FIG. 6; and

FIG. 11 is a perspective view of the embodiment of FIG. 6.

FIG. 1

FIG. 2

FIG. 3

FIG. 5

FIG. 4

FIG. 6

FIG. 7

FIG. 8

FIG. 9

FIG. 10

FIG. 11
